BOWLING PIN ELEVATING MECHANISM

Henry W. Phillips, Kenmore, N. Y., assignor to
 American Machine & Foundry Company, a corporation of New Jersey

Application June 23, 1948, Serial No. 34,695

20 Claims. (Cl. 273—43)

1

This invention relates to machines for automatically performing the functions of a pin boy on a bowling alley, and more particularly to apparatus for removing and conveying bowling pins from the pit at the back end of a bowling alley and delivering them to a suitable pin distributor of an automatic bowling pin setting machine.

When automatic mechanism is employed for performing the functions of a pin boy, it has to be fast and reliable and it must also handle the bowling pins gently to minimize wear and tear on the pins. This invention constitutes an improvement in the mechanical art of separating the bowling pins from the bowling ball and then conveying the pins from the pit of a bowling alley to a suitable distributing apparatus which replaces them back on the bowling alley at the proper time.

It is therefore an object of this invention to provide a bowling pin elevating device which will automatically pick up and remove bowling pins from the back end of the bowling pin setting machine which will be fast and accurate and which will prevent bowling pins from jamming in the bowling pin setting machine.

It is a further object of this invention to provide improved pin deflecting mechanism which will divert pins from an area where they have a tendency to jam and means for stopping the operation of the driving mechanism where the pin deflector has failed to prevent the jam.

Another object is to provide a deflecting device at the bottom of the bowling pit which will direct bowling pins into the range of operation of the flights of a pin elevator.

Another object is to provide pin elevating mechanism which will travel along a continuous endless path which is substantially rectangular in shape and forward pins lengthwise to a pin delivery station.

A further object is to provide a pin elevator consisting of a pair of spaced apart chains between which pin conveying flights are supported at spaced intervals at their centers.

Another object is to provide pin elevating flights which have curved pin supporting surfaces which engage with the end of the pin to prevent it from sliding off the flight as it goes around a curved path of travel.

Another object is to provide a pin elevating device at the back end of a pin setting machine which will have a pair of rails along its lowermost horizontal path of travel on to which bowling pins are pushed from the bottom of the pit.

2

These rails are so constructed that they are substantially on the same level as the bottom of the pit and slightly below the top of the carpet to thereby avoid pins piling on top of one another and yet provide a definite trough to help guide them as they are forwarded out of the pit.

A further object is to provide flights which will have fingers adapted to pass inwardly and downwardly beyond the rails of the pin elevator so that as the flights are disengaged from the rails and travel upwardly the fingers will positively support the end of the pin as it is being lifted lengthwise upwardly.

Another object is to provide a housing enclosing the flights of a pin elevating chain on all sides along that portion of its path of travel where bowling pins are elevated vertically from the bottom of the pit to support the pins pushed upwardly by the flights and prevent them from falling sidewise.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

Fig. 1 is a front elevation on an enlarged scale of the upper portion of the pin elevating and conveying mechanism with certain portions broken away for clarity.

Fig. 2 is a front elevation on an enlarged scale of the lower portion of the pin conveying mechanism with certain portions being broken away for clarity.

Fig. 3 is a rear view of the pin elevating mechanism and associated parts as seen from the back end of the machine.

Fig. 4 is a side elevation of the pin elevating mechanism.

Fig. 5 is a sectional plan view of the pin elevator mechanism taken on the line 5—5 of Fig. 2.

Fig. 6 is a partial side elevation illustrating the lower run of the pin conveyor and the adjacent portion of the carpet taken on line 6—6 of Fig. 5.

Fig. 7 is a partial front elevation illustrating the pin diverting device for moving pins from the right corner of the pit towards the center taken on the line 7—7 of Fig. 5.

Fig. 8 is a partial sectional side elevation of the pin conveyor mechanism as taken on line 8—8 of Fig. 1.

Fig. 9 is a partial side elevation illustrating the pin guide taken on the line 9—9 of Fig. 1.

Fig. 10 is a sectional front elevation illustrating on a larger scale the pin guide shown in Fig. 9 taken on the line 10—10 of Fig. 9.

Fig. 11 is a partial front elevation of the pin elevator shaft illustrating the pin deflector and safety switch mechanism for stopping the pin elevator.

Fig. 12 is a partial side elevation, partly in section, illustrating the pin deflector and safety switch mechanism.

Fig. 13 is a partial sectional side elevation of the pin deflector mechanism, taken on line 13—13 of Fig. 11.

Fig. 14 is a cross section illustrating a portion of the pin guiding tube and a flight attached to the elevator chain taken on line 14—14 of Fig. 1.

Fig. 15 is a cross sectional side elevation showing a flight of the pin elevator.

Various machines have been developed for mechanically performing the functions of a pin boy at a bowling alley. Machines of this general type, clear a bowling alley of standing and fallen pins or of just fallen pins in accordance with the rules of the game, pick up the thrown bowling ball and return it to the player along a ball return runway and place a new set of pins on the alley at the proper time.

The present invention provides an improved type of pin conveyor for unscrambling and removing pins from the pit of an alley and elevating the pins for delivery to a suitable magazine preliminary to their being spotted upon the alley. This invention is therefore especially well adapted for incorporation with automatic pin setting machines.

My apparatus for removing bowling pins from the pit of a bowling alley is preferably mounted to one side of the pit. In the embodiment I have used, I have for purposes of illustration shown this side to be the back end of the pit P.

In the course of the game of bowling, balls and pins at certain intervals are swept from the alley 10 into the pit P. The pins and balls are then forwarded by suitable means to the side of the pit where the pin elevator is located. A suitable cushion or ball bumper 14, for stopping a thrown bowling ball, is supported at its upper end by studs 15 which project from suitable brackets 16 fixed to a skeleton frame 26 of the bowling pin setting machine (Fig. 4).

Abutments 18 are mounted on the bottom of bumper 14 at opposite sides for holding the bumper in place. Suitable guide studs 20 projecting from the abutments 18 slide inwardly into openings formed in brackets 22 which are attached to the skeleton frame 26. Suitable compression springs 24 are mounted inside of the bracket 22 and coact with the sliding studs 20 to absorb the shock and movement of the ball bumper 14 when a thrown bowling ball strikes the bumper 14.

The pin conveying and elevating mechanism for removing the bowling pins from the pit P is mounted in that portion of the skeleton frame 26 which extends across the back end of the bowling alley. The pin conveyor and elevator consists of a pair of spaced sprocket chains 28 and 30 traveling over pairs of spaced sprockets 32 along a substantially rectangular path of travel thereby utilizing space which would usually be wasted.

The sprocket chains 28 and 30 are tightened by means of a suitable tensioning device consisting

of bars 34 which are slidably mounted in brackets 36. Brackets 36 are attached to the framework 26. An adjusting screw 38 having a lock nut 40 is provided for moving the sliding bar 34 in and out of the bracket 36. Sprockets 28a are mounted on the end of each of the sliding bars 34 and engage with the sprocket chains 28 and 30.

Driving movement is imparted to the sprocket chains 28 and 30 from a motor 42. A pulley 44 is mounted on the shaft 46 of motor 42 and imparts driving movement to a belt 48 traveling over the drive pulley 50. The drive pulley 50 is fixedly mounted on a shaft 52 which is rotatably mounted in suitable bearing brackets 54 and 56 supported by the skeleton framework 26. A sprocket 58 (Figs. 1 and 4) is fixedly mounted on the shaft 52 and imparts driving movement through the sprocket chain 60 to the sprocket 62.

Sprocket 62 is fixedly mounted on the shaft 64 to which is also fixedly connected another speed reducing sprocket 66. Shaft 64 is supported in suitable bearings carried by the skeleton framework 26. Sprocket 70 is driven from the sprocket 66 through a sprocket chain 68. The sprocket 70 is fixedly mounted on the shaft 72 which is rotatably mounted in suitable bearings 74 and 76 fixed to the skeleton framework 26. Sprockets 78 and 80 are also fixedly mounted on the shaft 72 and impart traveling movement to the sprocket chains 28 and 30.

Pin engaging flights 82 are fixedly connected at spaced intervals at their centers between the sprocket chains 28 and 30 (Fig. 12). A pair of rails 84 are mounted between the sprocket chains 28 and 30 where they are trained to travel along a horizontal path of travel at a level slightly below the horizontal carpet 12 as shown in Fig. 6. Each flight 82 has fingers 82a on one side which pass along the sides of rails 84 as they travel horizontally across the delivery end of conveyor 12. Rails 84 form the bottom of a trough the side walls 86 and 87 of which have chain channels 88 and 89 (Fig. 6). The wall 87 has an inclined guide 89 which causes pins received from the carpet 12 to roll or slide into the pin receiving trough mentioned.

The carpet or belt 12 travels in the direction indicated by the arrow over a pair of spaced rollers 91 (Figs. 4 and 6). The roller 91 at the far end of the pit (Fig. 4) is fixedly mounted on the shaft 90 which is supported in suitable bearings attached to the skeleton framework 26 of the automatic pin setting machine. Sprocket 92 (Fig. 2) is fixedly mounted on the shaft 90 and is driven by means of sprocket chain 94 from the sprocket 96 (Figs. 1 and 4). Sprocket 96 is fixedly mounted on a shaft 98 having conventional universal joints 100 and 102 to allow for differences in alignment between the bearing 104 mounted on the framework 26 and bearing 106 of the spur gear box 108.

The gears in the spur box 108 are driven by a shaft 110 connected to the bevel gear box 112 (Fig. 3). The gears in the bevel gear box 112 are driven by a shaft 114 to which is fixedly attached the sprocket 116. Sprocket 116 is driven from a sprocket 118 through sprocket chain 120. Sprocket 118 is fixedly mounted on shaft 122 which is rotatably supported in suitable bearings fixed to the skeleton frame 26. Sprocket 124 is fixedly mounted on the shaft 122 and receives driving movement through the sprocket chain 128 from the sprocket 126 (Fig. 4) which is fixedly mounted on the drive shaft 52. A suitable

sprocket 130 may be provided for tightening chain 128.

To prevent pins from coming to rest in the right hand corner of the pit where the flights 82 commence traveling upwardly, a pin deflector is provided for directing pins away from this corner towards the center of the carpet 12. This pin deflector consists of a pair of paddles 132 and 134 which are fixedly mounted on a sprocket chain 136, traveling over spaced sprockets 138 and 140. Sprocket 140 is fixedly mounted on the shaft 142 which is supported in suitable bearings fixed to the skeleton framework 26 of the automatic pin setting machine.

A second sprocket 141 (Fig. 4) is also fixedly mounted on shaft 142 and is driven by a sprocket chain 144 from the sprocket 146. Sprocket 146 is fixedly mounted on the shaft 148 which is supported in suitable bearings connected to the skeleton framework 26 of the pin spotting machine. A drive sprocket 150 (Fig. 4) is also fixedly mounted on the shaft 148 and engages with the sprocket chain 30 between two of the guide sprockets 32 as shown in Fig. 2. Paddles 132 and 134 are therefore driven each time that the conveyor chain 30 of the pin elevator is driven.

Pins discharged into the pit P are forwarded by the paddles 132 and 134 and the traveling carpet 12 over the guide plate 89 (Fig. 6) into the trough made up of walls 85 and 87 and the rails 84. Pins so discharged are engaged by the traveling flights 82 and moved lengthwise along the horizontal rails 84 and up along the inclined rails 84a (Fig. 2). A continuation of guide walls 85 and 87 is provided on either side of the inclined rails 84a to form a U-shaped channel for the pins. The upper ends of rails 84a extend under a guide plate 158 so that the pins are guided by the guide plate 158 at this point instead of by rails 84a and the horizontal guides 85 and 87 connect with the vertical side plates 154 and 156 respectively. At this area the pins are supported in a U-shaped trough made up of side plates 154 and 156 and the bottom guide plate 158 as shown in Figs. 2 and 5.

As the pins are pushed upwardly by the flights 82 they gradually assume a position which is substantially vertical as shown in Fig. 12. When a pin reaches this position if the upper portion of the pin tilts outwardly from the U-shaped channel, as shown in Fig. 12, it will either be pushed away from the flight 82 by the pin deflector 186 or will be guided into the rectangular tube made up of cover plate 152 and a U-shaped channel consisting of side walls 154, 156 and the back plate 158. The side walls 154 and 156 have suitable chain supporting channels 160 and 162 (Fig. 5) through which the sprocket chains 28 and 30 travel upwardly.

The pin deflector 186 is pivotally connected to a swinging bracket 164 which is fixedly mounted on the shaft 166. Shaft 166 is freely supported in suitable bearings 168 and 170 formed in two downwardly projecting lugs 169 and 171 of bracket 172 (Fig. 11). Bracket 172 is connected by suitable screws 174 and 176 to the sidewalls 154 and 156 of the tubular housing through which the flights 82 travel. A cam 178 for stopping the pin elevator in case of a jam is fixedly mounted on one end of shaft 166 as shown in Fig. 11. Torsion spring 180 is connected at one end to the cam 178 and at the other end to the lug 171 and is not active in its neutral position shown in Fig. 12. The spring 180 serves to yieldably urge the swinging bracket 164 to its vertical position when it is engaged by a bowling pin.

The pin deflecting plate 186 is mounted on a shaft 188 which is pivotally supported in bearings formed in the lower end of the swinging bracket 164. A stop 190 is provided to limit the distance plate 186 can swing downwardly under the action of gravity away from the swinging bracket 164. The upper end of the plate 186 has a bent portion 192 which is movable into engagement with the two downwardly projecting lugs 169 and 171. The lower end of the plate 186 has a curved portion 194 which curves around the shaft 188 to provide a smooth pin engaging surface.

When a bowling pin is raised upwardly as shown in Figs. 12 and 13 there is a possibility that the pin supported on the flight 82 will not be exactly vertical as the leading end of the pin is about to be pushed into the enclosed tubular passage made up of the plates 152, 154, 156 and 158. In this case if the upper end of the pin does not project too far outwardly it will engage with the yieldable plate 186 which will cam the head of the pin into the tubular housing mentioned. On the other hand if the pin projects outwardly beyond a certain point it will engage with the curved section 194 of plate 186 and cause the swinging bracket 164 to swing on its pivot shaft 166 as shown in dotted outline in Fig. 12. The pin will then be pushed out so that it falls away from the flight 82 and falls towards the bottom of the pit where it will be picked up again by another flight traveling along the horizontal plane in said pit.

If it should so happen that a pin should jam between the flight 82 and the swinging bracket 164 it will cause the bracket 164 to swing outwardly to such an extent that the cam 178 engages with the roller 196 of a trigger arm 198 and depresses the same. The roller 196 is pivoted to the trigger arm 198 which actuates a conventional electrical switch 200. When the switch 200 is actuated, as will be hereinafter explained, the traveling movement of conveyor chains 28 and 30 to which the flights 82 are attached is stopped so that the jammed bowling pin can be removed before it causes any damage. The yieldable pin deflector 186 normally pushes the leading end of the pin being elevated either into the tubular housing made up of plates 152, 154, 156 and 158 as shown in Fig. 13, or pushes it away from the flight 82 as shown in Fig. 12 before it has a chance to become jammed. In other words the yieldable deflector 186 normally prevents the pins from becoming jammed and the switch 200 is merely provided as a safety factor in the event the pin deflector fails to prevent the jam.

As the pins are elevated upwardly inside the tubular passage made up of cover plate 152, side plates 154 and 156 and back plate 158, the pins reach a curved channel area 202 (Fig. 1). The cover plate 152 at this area has a trough shaped section 204 (Fig. 14) formed to facilitate the travel of the pins around this curved path of travel. As the pin reaches the top of this curvature it is discharged from the flight 82 onto an inclined guide plate 206 from where the pin slides downwardly into contact with another guide plate 208 which diverts said pin in between the conveyor belts 210 and 212. Some pins come up through the tubular housing 152, 154, 156 and 158 head first while others come up through the tubular housing bottom first as shown in Fig. 12.

As soon as the pin falls in between the traveling conveyor belts 210 and 212 the pin is carried along by the movement of the belts 210 and 212 in the direction indicated by the arrow in Fig. 4. A pin

guide plate 216 is positioned between the conveyor belts 210 and 212 so that the head end of the pin will trail on top of this plate 216 as its body rests on and travels along with the conveyor belts 210 and 212.

One end 218 of the pin supporting plate 216 is curved so that when a bowling pin is dropped in between the conveyor belts 210 and 212 it will be oriented when it strikes the curved portion 218. For example if the pin is delivered head first in between the conveyor belts 210 and 212 the head end of the pin will strike the curved plate 218 so that the bottom end of the pin is moved forward. If on the other hand the bottom end of the pin is delivered to the belts 210 and 212 first the belts 15 will engage and pull the bottom end of the pin forward first so that the head end of the pin will again fall towards the rear. All pins therefore will be delivered bottom first to a suitable pin distributor (not shown) which may be associated with the delivery end of the conveyor belts 210 and 212.

The conveyor belts 210 and 212 travel over spaced pulleys 222 and 224 (Fig. 4). A third pair of pulleys 226 are provided for draping the belts 210 and 212 around the spaced drive pulleys 222.

Pulleys 224 and 226 are freely mounted on shaft 223 and studs 225 respectively supported by the skeleton framework 26 of the bowling pin setting machine. The drive pulleys 222 are fixedly mounted on the shaft 110 which is supported between the spur gear box 108 and the bevel gear box 112. Rotary movement is imparted to the shaft 110 from the bevel gear box 112.

Operation

The operation of my invention may be briefly described as follows:

After a bowling ball is thrown by a player it actuates a suitable detecting device such as a photoelectric cell which sets the bowling pin setting machine into operation. In the course of operation, a sweep such as that shown in U. S. Patent 2,250,503 sweeps pins from the bowling alley into the pit P. The bowling ball either by its own momentum or by the action of the sweep is also deposited into the pit P.

Movement of the belt 12 forwards the pins and bowling ball discharged into the pit P towards one side thereof. In the present disclosure I have shown how the ball and pins may be conveniently moved to the rear of the pit, but in actual practice whichever side is most conveniently suitable for use with the machine employed can be used.

Since the bottom of the bumper 14 is spaced from the carpet 12 a distance less than the diameter of a bowling ball the ball is stopped from further movement when it engages with the bumper 14.

Bowling pins on the other hand, having a diameter less than the distance between the bumper 14 and the carpet 12, are forwarded under the bumper 14 onto the plate 89 from where they roll and slide onto the rails 84 forming the bottom of the channel which is enclosed by side walls 85 and 87.

One of the main purposes of my invention is to decrease wear and tear on the bowling pins and to quickly effect their separation and removal from the pit. I have accomplished this by providing a troughlike channel along the side of the pit into which pins are pushed. By making the width of the channel and flights 82 approximately the size of the widest diameter of a bowling pin, bowling pins are aligned by sliding into the chan-

nel and also by the rectilinear movement of the flights 82.

It will be noted that the distance the pins roll from the belt 12 into the channel referred to is very small thereby minimizing pin wear. By spacing flights 82 a distance greater than the length of a bowling pin and less than the length of two bowling pins each flight 82 can only elevate one bowling pin at a time. As a consequence undesirable tumbling caused by several pins being carried upwardly by a flight and then falling back into the pit has been prevented.

I find that by extending the channel adjoining the side of the pit floor 12 along the greater length thereof, the pickup capacity of the conveyor flights is increased since several pins may be simultaneously received by different flights and forwarded along at the same time.

Looking towards the back of the machine in the lower right hand corner where the tracks 84a commence traveling upwardly as shown in Fig. 2 there is a possibility that pins could become immobilized in this corner. A similar possibility for this to happen might occur in the 25 left hand corner of the machine where the flights change from a downward to a horizontal path of travel. To avoid this, I have provided suitable pin deflectors in the form of paddles 132, 134 and camming plates 131 and 135 (Figs. 5 and 7). The paddles 132, 134 and cam plates 131 and 135 divert pins heading for these corners towards the center of a carpet 12 which forwards them onto the horizontal portion of rails 84.

The camming plates 131 and 135 and traveling paddles 132 and 134 may be advantageously used with other types of pin elevators to improve their reliability by providing positive means for avoiding the immobilization of pins in blind corners. To be successful an automatic pin setting machine must be fool proof to dispense with the need of a pin boy and should not require a machine attendant to take his place.

When the pins reach the end of their travel on rails 84 they commence traveling along the inclined rails 84a (Fig. 2) and rear guide plate 158 which causes the forward end of the pin to assume a more or less vertical position. At the area where the pin changes its direction of travel in this manner the curvature of the pin engaging flight 82 (Fig. 12) supports the bottom of the pin so that the pin can swivel thereon and is prevented from sliding along the flight when the flight and pin travel around a curve. This has the advantage that the end of the pin engaging with the pin engaging flight 82 is more or less centrally located at all times with respect to the flight thereby avoiding unnecessary contact and wear with the side guides surrounding the path of travel of the flights 82.

As the pin continues its further upward movement it enters into an inclined tubular housing made up of the cover plate 152, the back plate 158 and the side plates 154 and 156. Since the back or pin guiding plate 158 is inclined the cover plate 152 could be omitted if desired. In the event that the leading end of a pin being elevated by a flight 82 is positioned at an angle away from the pin guiding wall 158, it will strike against a second pin deflecting device shown in the form of a yieldable plate 186. If the pin inclines at a very great angle it will strike the curved portion 184 of the yieldable plate 186 and thereby be pushed away from the flight 82. On the other hand if the misalignment is only slight, then in that case the pin will be cammed

by the plate 186 back into correct alignment as shown in Fig. 13.

The yieldable pin deflector 186 is positioned at the entrance to the pin elevator housing in the manner shown in Fig. 2 to prevent jams by either removing misaligned pins or by correcting their misalignment before entering the tubular housing mentioned.

If desired, a safety switch such as 200 may be associated with the deflecting plate 186 to incapacitate the pin elevator in the event that the plate 186 should fail to correct a misaligned pin by effecting its removal or by correcting its position. In Fig. 12 I have shown how such a safety switch can be mounted. In the event a jam should take place the bracket 146 supporting the pin engaging plate 186 will be moved away from its normal position to such an extent that the cam 178 will engage with the roller 196 of trigger arm 198 which actuates the switch 200 to bring the pin elevator to a stop.

The upper end of the tubular housing 152, 154, 156 and 158 has a curved portion 202 which directs the pin towards the inclined guide plate or slide 206. The cover plate 152 is outwardly convex as shown by the reference character 204 (Fig. 14) to facilitate the pin traveling around this curved section 202 of the tubular housing by providing adequate clearance and guidance for the pin.

When the pin has been discharged onto the slide 206 it slides lengthwise downwardly into contact with guide plate 208 which directs the leading end of the pin in between the orienting belts 210 and 212. If the bottom end of the pin is delivered to the belts 210 and 212 first the movement of belts 210 and 212 traveling in the direction indicated in Fig. 4 causes the bottom end to be forwarded first with the head end trailing behind on top of the guide plate 216.

If the head end of the pin is delivered to the belts 210 and 212 first the body of the pin is engaged by the belts 210 and 212 and the head end is held back by the curved end 218 of the guide plate 216 thereby causing the bottom end of the pin to be forwarded first with the head end trailing behind.

The invention above described may be varied in construction within the scope of the claims, for the particular device selected to illustrate the invention is but one of many possible embodiments of the same. The invention, therefore, is not to be restricted to the precise details of the structure shown and described.

What is claimed is:

1. Apparatus for removing bowling pins from the pit of a bowling alley and delivering them lengthwise to the pin setting mechanism of an automatic bowling pin setting machine comprising a pin receiving trough extending horizontally along most of the length of one side of the pit and having the bottom thereof at substantially pit floor level, said trough having a width which limits bowling pins received in said trough to lengthwise travel, means forwarding bowling pins from the pit directly to said trough, a pin conveying device having flights traveling along said trough and along a substantially perpendicular path of travel connecting with said horizontal trough to carry bowling pins lengthwise first horizontally and then upwardly out of the pit, a tubular housing surrounding said pin conveyor along its perpendicular path of travel to confine said pins to lengthwise movement, a pin deflector mounted at the entrance to said tubular hous-

ing for positioning or removing bowling pins not properly positioned on the flights of the pin conveying device, said deflector being constructed and arranged to be movable along at least two different paths in the same plane, and a drive for moving said conveying device along said horizontal and vertical paths of travel.

2. Apparatus for removing bowling pins from the pit of a bowling alley and delivering them to the pin setting mechanism of an automatic bowling pin setting machine comprising, a bowling pin conveyor traveling in a closed path of travel, the lowermost portion of said path of travel being horizontally along substantially the entire length of one side and at substantially the level of the pit floor and another portion of said path being in an upward direction leading from the end of said horizontal path of travel, a pin receiving channel formed along the side of said pit where said conveyor travels so that the bottom of the channel is at substantially pit floor level, a plurality of elongated rails positioned in said channel for supporting pins, means for moving pins directly from the pit floor to said channel, flights connected to said conveyor and extending transversely across said channel for engaging and moving bowling pins along said channel, a guide through which bowling pins elevated by said flights are conveyed after leaving the horizontal portion of said path of travel, and driving mechanism for moving said flights along said horizontal and vertical paths of travel.

3. Apparatus for removing bowling pins from the pit of a bowling alley and conveying them to a pin distributing apparatus for replacement on the bowling alley in playing arrangement comprising, a pin receiving trough having the bottom thereof extending along and at substantially the same level as the pit floor, said trough having a width slightly larger than the diameter of a bowling pin to restrict said pins to lengthwise travel, means for discharging bowling pins directly from said pit floor into said trough, a pair of spaced endless sprocket chains, sprockets for guiding and confining said chains to a substantially quadrilateral path of travel, and having a portion of said path of travel extending along said trough and another portion of said path being vertical with respect to said trough, flights positioned to have the center portion of the flight engage with the end of a bowling pin when elevating the pin lengthwise between the chains, supports fixedly connecting the opposite sides of said flights at their center to the sprocket chains to minimize movement between the center of the flight and the end of the pin when pushing bowling pins around curves, and a drive moving said sprocket chains to bring said flights into engagement with the ends of bowling pins discharged into said trough and thereby elevate the pins from said trough upwardly to a pin receiving device.

4. Apparatus for removing bowling pins from the pit floor of a bowling alley and conveying them to a pin setting apparatus of a bowling pin setting machine comprising, a pair of spaced endless sprocket chains, a pin receiving trough having a width slightly larger than the diameter of a bowling pin positioned adjacent and at substantially the same level as said pit floor for confining said pins to lengthwise travel, sprockets for confining said chains to an endless path of travel, a portion of said path of travel being adjacent and substantially level with the side of the floor of the pit and in said trough and

another connecting portion of said path of travel being at an angle thereto to form a curve, mechanism for forwarding pins from the pit directly to said first named portion of the sprocket chain path, flights connected at their centers between said sprocket chains at predetermined spaced intervals, said flights having a concave surface engaging with the ends of bowling pins and pushing them along the path of travel of said sprocket chains for a predetermined distance, said concave surface having a curvature to minimize movement between said surface and the end of a bowling pin when pushing a bowling pin around said curve, and a drive for imparting traveling movement to the flights and sprocket chains to move pins so engaged from said trough upwardly to a pin receiving device.

5. In a bowling pin setting machine, a pin conveyor for moving pins lengthwise along a predetermined path of travel, a portion of which is substantially horizontal and another portion connecting therewith being substantially vertical, a tubular housing surrounding the vertical portion of said pin conveyor, flights mounted at spaced intervals on said conveyor for engaging with the ends of bowling pins, a pivoted member mounted at the entrance to said tubular housing and adjacent to the path of travel of said flights to push greatly misaligned pins off said flights, a second pivoted member having a flat surface and swingably connected to the first pivoted member so as to dispose said flat surface in position to engage and correctly position slightly misaligned pins, and a drive for moving said flights upwardly through said tubular housing.

6. A device for removing bowling pins one at a time from the pit of a bowling alley comprising, a pair of spaced elongated pin guiding rails extending adjacent and substantially level with one side of the pit floor and then upwardly forming a curve and adapted to receive bowling pins therebetween and thereby constrain pins sliding thereon to lengthwise movement, a conveyor having a path of travel along said rails, a forwarding device for moving pins across the pit floor directly onto said rails, pin engaging flights connected at their middle to said conveyor and passing over said rails to slide said pins lengthwise on said rails, said flights having surfaces which are concave at least in the direction of said curve with respect to the ends of bowling pins with which they engage to provide a transverse support for the end of the pin when the pin is conveyed by said flights around said curve, and a drive moving said conveyor and flights along said rails to push bowling pins deposited on said rails lengthwise out of said pit.

7. A device for removing bowling pins one at a time from the pit of a bowling alley comprising, a conveyor having flights with pin engaging areas of a size approximating the largest diameter of a bowling pin, mechanism for guiding said flights along a path of travel adjoining and substantially level with one side of the floor of the pit, means for delivering bowling pins directly from the pit floor to said flights, a wall extending along and closely adjacent the path of travel of said flights for restricting pins pushed by said flights to lengthwise travel, an upwardly inclined U-shaped channel for receiving and guiding bowling pins pushed by said flights, a pin guiding tube connecting with the end of said U-shaped channel, and conveyor drive mechanism moving said flights along a continuous path of travel to push bowling pins endwise in front of said flights through said

U-shaped channel and tube to a pin receiving apparatus.

8. A device having the features provided for in claim 7 and a pin deflector positioned adjacent the area where said tube connects with said U-shaped channel to deflect any pins which are not properly positioned to enter said pin guiding tube away from said flights.

9. A device having the features provided for in claim 7 and a movable pin deflector positioned adjacent the area where said pin guiding tube connects with said U-shaped channel to deflect any pins which are not properly positioned to enter said tube away from said flights, a conveyor incapacitating device, and a switch positioned to be actuated by said deflector to actuate said conveyor incapacitating device when it is pushed by a pin beyond a predetermined distance.

10. Apparatus for removing bowling pins from the pit of a bowling alley comprising, means for continuously moving bowling pins lying on the floor of the pit to one side of the floor of the pit, a wall spaced from said side a distance causing bowling pins to move lengthwise therebetween, 20 a conveyor having flights for engaging with the ends of bowling pins discharged into the space between said wall and the side of the pit, an upwardly inclined chute connected with said space, a conveyor drive moving said flights along the side of said pit to advance bowling pins lengthwise along said space and up along said chute, and a deflecting device positioned in said pit adjacent to said inclined chute for diverting pins being moved by said means from the corner of 30 said pit towards the flights of said conveyor.

11. Apparatus for removing bowling pins from the pit of a bowling alley comprising, a channel having a width approximating the largest diameter of a bowling pin and a length extending 40 along and substantially level and adjacent with the greater part of one side of the pit floor, said channel having a depth approximately the diameter of a bowling pin, pin engaging flights spaced from each other a distance sufficient to allow only one pin to fit in lengthwise between said spaced flights and be forwarded thereby, means moving the pins directly from the pit floor to said channel to be engaged by said flights, a second channel connected at an incline with said first named channel for directing pins lengthwise to a pin delivery station, and a drive moving said flights in a continuous path the lowermost portion of said path passing through said first named channel to forward pins lengthwise along said first and second channels.

12. Apparatus for removing bowling pins from the pit of a bowling alley and elevating them to a pin discharge station, said apparatus comprising a flexible member arranged to travel in an 60 endless path, the lowermost portion of said path extending a substantial distance parallel and substantially level with and adjacent the length of one side of the pit floor of the bowling alley and another portion of said path connecting with said first portion and extending vertically to a pin discharge station, guides positioned adjacent said portions of said path of travel to confine said pins to lengthwise travel, pin engaging flights mounted on said flexible member at intervals sufficient to 65 receive the length of a bowling pin therebetween, and means for forwarding bowling pins directly from the pit floor to the side of the pit where the pins are deposited between said flights and forwarded lengthwise to said pin discharge station.

13. Apparatus for removing bowling pins from the pit of a bowling alley and elevating them to a pin discharge station, comprising a U-shaped pin receiving channel having a cross sectional width and depth approximating the largest diameter of a bowling pin extending along one side and at substantially the same level as said pit, means for moving bowling pins from the floor of the pit along a substantially horizontal plane directly into said U-shaped channel, and a plurality of spaced pin engaging flights moving in a closed path the lower run of which travels along said U-shaped channel to forward pins lengthwise along said channel, said flights being operative to advance bowling pins to said pin discharge station.

14. Apparatus for removing bowling pins from the pit of a bowling alley and conveying said pins to a pin delivery station, said apparatus comprising, a race the bottom of said race extending adjacent and at substantially the same level as one side of the pit of a bowling alley, said race being of a width sufficient to confine said pins to a lengthwise path of travel, a pin delivery station located at a distance from said race, pin pushing flights traveling in an endless path, the lowermost run of said flights being along said race to forward bowling pins lengthwise therealong, said flights being operative to advance bowling pins to said pin delivery station, and mechanism for forwarding pins located in said pit along a plane substantially the same as the pit floor directly to said race.

15. Apparatus for removing bowling pins from the pit of a bowling alley and raising them to a pin delivery station, said apparatus comprising a race the bottom of which extends along and adjacent and at substantially the same level as one side of the floor of the pit, said race having a width and depth approximately the diameter of a bowling pin, means for diverting pins on said floor toward the center portion of said race, means including said diverting means for forwarding pins on said pit floor directly to the race, and pin engaging flights traveling in a closed circuitous path for engaging and forwarding pins lengthwise to said pin delivery station, the lowermost portion of said path extending along said race, whereby said flights forward pins lengthwise along said race to said station.

16. A device for removing bowling pins one at a time from the pit of a bowling alley comprising, a bowling pin receiving trough extending along, adjacent, and the bottom thereof being at substantially the same level as one side of said pit, the sides of said trough being spaced to confine a bowling pin to lengthwise movement therebetween, pin engaging flights spaced at a distance allowing only one bowling pin at a time to be moved lengthwise between each pair of said flights, means confining said pin engaging flights to an endless circuitous path of travel, the lowermost portion of said path of travel of said flights being along said trough, and apparatus for delivering bowling pins on the floor of said pit directly from the floor of said pit into said trough.

17. A device for removing bowling pins one at a time from the pit of a bowling alley comprising, a pin receiving trough extending adjacent, along, and at substantially the same level as one side of the pit, said trough being of a width and depth which is approximately equal to the diameter of a bowling pin, a pin delivery station, pin supporting rails extending along the bottom of said trough and at approximately pit floor

level, flights movable along said trough to slide pins lengthwise along said rails, means for moving said flights in a closed path along a horizontal and an upward path of travel between said pit and said pin delivery station, the lowermost portion of said path of travel being horizontally along the length of said trough, means supporting each of said flights at opposite sides at the middle of the flight to provide transverse support for the ends of pins when being moved from a horizontal to an upward path of travel, and mechanism for forwarding bowling pins lying on the floor of said pit directly therefrom onto said rails in the path of travel of said flights.

18. Apparatus for removing bowling pins from the pit of a bowling alley and delivering them to a pin receiving station located at an elevation higher than the pit floor, said apparatus comprising, a trough extending along and at substantially the same level as one side of the pit floor for receiving bowling pins discharged from said pit floor into said trough and restricting them to endwise travel, a conveyor traveling in a path along said trough to said pin delivery station, a portion of the conveyor path from said trough to said pin delivery station being curved causing bowling pins to be moved lengthwise in horizontal and vertical directions at different times, a drive for moving said conveyor along said path, and concave pin engaging flights connected at predetermined intervals to said conveyor, said flights being disposed transversely of the conveyor, and being cylindrically concave about a transverse axis, the concave surface facing in the direction of movement of the flights, said concave curvature being sufficient to cause the end of a bowling pin engaged by a flight to remain centered with respect to said flight by swiveling in said flight when the pin in being moved changes from a horizontal path of travel to a vertical path of travel.

19. Apparatus for removing bowling pins from the pit of a bowling alley and elevating them to a pin receiving station located at an elevation higher than the pit floor comprising, an elongated trough having a width and depth approximating that of the diameter of a bowling pin, said trough extending horizontally along the major portion of the length of one side of the pit and the bottom of which is at substantially the same level as the pit floor to receive bowling pins directly from the pit floor, spaced pin engaging flights traveling first horizontally along said elongated horizontal trough and then upwardly towards said pin receiving station, a drive for moving said flights in an endless continuous path along said trough to said pin receiving station and back again, the lowermost portion of said continuous path passing through said trough to forward pins lengthwise therealong, pin deflectors mounted over said pit floor adjacent opposite ends of said trough for deflecting bowling pins horizontally along said floor from the sides of said pit towards the center of said trough, and means including said deflectors for moving bowling pins located on the floor of said pit directly into said trough.

20. A device for removing bowling pins one at a time from the pit of a bowling alley comprising a conveyor having flights with pin engaging areas, mechanism for guiding said flights along a path of travel adjoining and substantially level with one side of the floor of the pit, means for delivering bowling pins directly from the pit floor to said flights, a wall extending along and closely

15

adjacent the path of travel of said flights for restricting pins advanced by said flights to lengthwise travel, an upwardly inclined guide channel for receiving and guiding bowling pins advanced by said flights, pin guiding means receiving pins from said guide channel, and conveyor drive mechanism moving said flights along a continuous path of travel to advance bowling pins endwise by said flights through said guide channel and pin guiding means to a pin receiving apparatus.
